Patented Feb. 22, 1916.

UNITED STATES PATENT OFFICE.

NORBERT H. SCHICKEL, OF STAMFORD, CONNECTICUT.

INTERNAL-COMBUSTION ENGINE.

1,172,314.

Specification of Letters Patent. Patented Feb. 22, 1916.

Application filed December 9, 1913. Serial No. 805,486.

To all whom it may concern:

Be it known that I, NORBERT H. SCHICKEL, a citizen of the United States, and resident of Stamford, in the county of Fairfield and 5 State of Connecticut, have invented certain new and useful Improvements in Internal-Combustion Engines, of which the following is a specification.

My invention relates to improvements in 10 engines of the internal combustion type designed to be used on motor-cycles and other motor vehicles and the general object thereof is to provide a motor of the kind mentioned which will possess features of superior adaptability to the purposes for 15 which it is intended.

A further object of my invention is to obtain a well-poised engine construction wherein the weight of the flywheel and the 20 parts by which power is transmitted from the motor, all of which are disposed on one side of the central longitudinal axis of the engine, will be balanced in part by the weight of the magneto, which furnishes the 25 ignition current, located on the other side of the central axis.

A further object of my invention is to align the armature shaft of the magneto with the engine shaft and connect the 30 former to be driven by the latter by an automatic compensating device which will at all times insure the proper operation of the magneto even though the alinement is not a perfectly true one.

Another feature of the invention resides 35 in the construction of the fly-wheel which is preferably made in one piece with the crank pin and the main shaft projecting centrally therefrom.

An additional object of my invention is to 40 mount the power shaft so that it will not have to support the weight of the fly-wheel and the transmission parts, but will be free from the influence of every force except the 45 torsional stresses due to the thrust of the engine piston.

A still further object of my invention is to 50 mount a tightening device for the belt which turns the driving wheel or wheels of the motor-cycle or vehicle in such position

on the engine that it will be part of the construction thereof, without occupying much space or being in the way of the other parts, and at the same time be capable of adjustment from the steering mechanism. 55

Yet another object of my invention is to form the crank casing of the engine with separate chambers in which the certain parts and accessories, such as the fly-wheel and the magneto, can be conveniently 60 housed, the chambers in question being provided with removable closures, so as to afford ready access thereto.

A still other feature is the provision of 65 a plate serving as a closure for the fly-wheel chamber, and being of sufficient size and strength to serve as a bearing for the power shaft and carry the weight of the flywheel and transmission devices which cause the 70 driving elements of the motor-cycle or vehicle to be operated.

Moreover, as my improved engine is preferably of the two-cycle type, I aim to reserve a sufficient amount of unoccupied space 75 in the crank casing, after all the parts are inclosed therein, to serve for the purpose of compressing air to force the fuel charge into the firing chamber.

These and other objects of the invention will appear more fully in the following detailed description taken in connection with the accompanying drawings, wherein the same characters designate the same parts in all the views, and wherein,

Figure 1 is a section on the line 1—1 of 85 Fig. 2 showing the lower part of the engine framework and particularly the compensating driving connection for the magneto; and Fig. 2 is a vertical or longitudinal section taken in a plane passing through the 90 axis of rotation of the power shaft showing the construction of my invention in all its parts.

I have not illustrated the main body of 95 the cylinder, piston, ports, igniter, etc., as these do not form any part of the invention hereinafter claimed and may be of any suitable character well-known to those skilled in the art. They may be and preferably are substantially as shown in my co-pending 100

application, Serial Number 735,464, filed December 6th, 1912.

In the specific embodiment of my invention, which I have illustrated and which 5 constitutes only one form which the invention may assume, I employ a power cylinder 1, mounted upon a crank casing 2, and in the cylinder moves a piston 3, joined by means of a connecting rod 4 to a flywheel 5, and main shaft 6, the flywheel having a 10 crank pin 7 which the end of the rod 4 engages.

The body of the crank case is cylindrical in form and has one end wall 10 which may 15 be substantially in line with the axis of the cylinder 1, the other end being open, and being provided with a plate 11 to close the same. This case has an extension 12, into the outer end of which the cylinder 1 is fitted 20 or to which it may be secured. The crank case proper houses the flywheel 5, which is driven by the piston, and the connecting rod 4 thus normally moves substantially in the plane of the wall or end 10. As the piston 25 reciprocates air is compressed in the crank case and expelled therefrom by way of a passage 13 formed by part of the side wall of the cylinder 1 and part of the wall of the lateral extension 12 above mentioned.

30 From the end wall 10 of the crank case projects an axial extension 14, which is closed at its inner end by a web or partition 15. This web 15 divides the space forming the flywheel and compression chamber in the 35 crank case from a similar chamber in the extension 14 which receives the magneto 16 furnishing current to the igniter of the engine. The outer end of the extension 14 is closed by a cover 17, which is removable, 40 like the plate 11, so that access to the flywheel and compression chamber or to the magneto chamber can be had at any time.

It is of course understood that the body 45 of the crank case with the extensions 12 and 14, and the partition 15 will be cast in one piece; or if preferred the partition may be a separate piece and be secured to the inside of the case by any preferred form of fastening devices. The inner end of the extension 50 12 merges on one side with the inner end of the extension 14 on the adjacent side of the same, and the crank case so formed makes a compact base or support for the power cylinder when the case is secured to the 55 framework of the motor-cycle, vehicle, or other support, on which the motor is to be used.

Referring now to the construction of the flywheel and the connections for the same, 60 it will be seen that the wheel 5, shaft 6 and crank pin 7 are also made in one piece, either by casting or forging. The shaft 6 projects out through the plate 11, and the pin 7 is surrounded by a collar 18. This collar is

preferably fixed on the pin, but may be loose 65 if desired. A second collar of larger diameter surrounds the first collar, and the adjacent cylindrical faces of the two collars are grooved to form a raceway for rolling elements 20. These rolling elements are shown 70 in the form of bearing balls, but obviously they may be shaped otherwise as conditions may require. A suitable strap is provided on the end of the rod 4 which encircles the ring 19, and thus a perfect anti-friction connection between rod 4 and the pin 7 is af- 75 forded.

In order to economize space, I form an annular recess 21 in the inside face of the flywheel around the pin 7. This recess has 80 an annular groove in its bottom which receives a wear ring 22. The ring 19 and the strap on the rod 4 which encircles this ring abut against the wear ring 22, and when the latter is worn out it can easily be replaced. 85 This wear ring will of course be made of some suitable soft metal. A suitable nut 23 is screwed upon the outer end of the pin 7 to keep the parts in place.

It will now be apparent from the above 90 description and from an inspection of Fig. 2 that the outer end of the piston rod moves in the space between the flywheel and the partition 15. The rod is located in close proximity to the flywheel, and just enough room is 95 left between the wheel and partition to allow the necessary clearance for the crank pin. This clearance room, in combination with the unoccupied space at the top of the crank case and at the inner end of the extension 12 100 makes up the compression chamber of the engine, and the compressed air, as stated above is forced out by the piston on the out-stroke through the passage 13.

The shaft 6 projects from the opposite 105 face of the flywheel, and this face is provided with an annular recess 24 concentric with the shaft, and with a dished surface 25. This surface 25 matches with the inner 110 face of the closure plate 11, which is shaped like a flat cone, and is provided at its center with an annular bearing boss. Into this bearing boss is fitted a tight bushing 28, which extends into the crank case and terminates at its inner end in a flange 29. The 115 shaft 6 passes through this bushing, and surrounding the same and receiving the shaft 6 is a jacket 30 which takes up the wear on the two parts. The bushing 28 carries the 120 weight of the flywheel and the transmission 125 devices outside the casing, so that the only stress which the shaft 6 has to endure is the torsion due to the rotation of the engine; and I attain this object, as well as reduce the friction in running, by an arrangement which will now be described.

Into the recess 24 is fitted a ring 31, and on the inner end of the bushing between the

flange 29 and the plate 11, I locate a smaller ring 32. The adjacent annular faces of these two rings are grooved to make a race-way, and into this raceway are placed rolling elements, preferably in the shape of bearing balls 33. A wear plate 34 is disposed between the rings 31 and 32 and the inner end of the bearing boss 27, and this plate contacts around its outer edge with a packing ring or other suitable packing device 35. The anti-friction bearing for the flywheel is thus snugly housed in the recess 24 and the flywheel hangs on the inner end of the bushing, the whole weight thereof being lifted from the shaft 6. Furthermore, the wheel is arranged to fit the body of the crank case and is completely inclosed and protected when the plate 11 is bolted in place.

20 The outer end of the shaft 6 is connected to the transmission devices by which power is communicated to the driving mechanism of the cycle or vehicle; and these transmission devices comprise mainly a belt pulley, 25 so mounted, that, like the flywheel, its weight is not borne by the shaft 6. This is accomplished by an anti-friction bearing including a ring 36, secured by screw threads or any other means to the outer end of the 30 bushing 28, and held in place by a lock nut or the like indicated at 37. The belt pulley 38, turned by the shaft 6, is fitted to the outer coned end 39 of the shaft 6, and is held thereon by means of a nut 41. 35 Obviously almost any other form of holding device will answer the purpose. The pulley has a recess 42 on its inner face, which receives the outer end of the bushing 28, with the ring 36 thereon, and into this recess is 40 also placed a ring 43 encircling the ring 36. These rings have raceways formed in their adjacent annular faces, the same as in the case of the bearing rings in the flywheel and around the crank pin, and into the raceway 45 so formed are placed the rolling elements 44. The weight of the pulley by this arrangement is thus taken off the shaft 6 entirely.

It will now be apparent that the weight of 50 the flywheel and pulley is borne by the bushing 28, and this is in turn carried by the plate 11, bolted to the crank case, which is secured to the framework of the motor-cycle or vehicle. The only stress borne by the 55 shaft 6 is the twisting force due to the rotation of the parts when the engine is in operation; and it will be further noted that the pulley outside the crank case will balance the weight of the flywheel inside, thus 60 obviating any tendency of the plate 11 to undergo buckling or other deformation.

In order to tighten the belt which passes over the pulley 38, I employ an idler which is mounted on a supporting plate adjustable

around the axis of the shaft 6, as a center. 65 For this purpose, I form an annular boss 45 on the outer face of the plate 11, this boss being in the center of the plate and receiving a bushing 46. The boss and bushing serve as a journal for a plate 47, which is 70 provided with a peripheral groove 48 to house a cord or wire leading to any suitable operating mechanism so that the plate 47 can readily be shifted. Obviously I may provide the plate 47 with a boss, and form a 75 groove in the plate 11 around the bushing 28, to receive such a boss, as an alternative method of mounting the plate 47 if desired. In either case the plate 47 is located between the plate 11 and the driving pulley, 80 forms a part of the engine structure, occupies but little space, and keeps the tightener in position to operate efficiently at all times when needed.

The plate 47 carries a stud or spindle 49, 85 screwed into the same or otherwise fastened thereto, and this spindle carries the idler 50 by which the actual tightening is effected. The outer section 51 of the stud 49 is reduced and screw threaded to receive a lock 90 nut 52, to keep the idler 50 on the stud, and the threads on the stud also receive a cone-shaped head coöperating with a flanged bushing 54 in the hub of the idler 50 to 95 form a raceway for an anti-friction bearing. A similar flanged bushing is carried in the opposite end of the hub of the tightening pulley and forms with the relatively thicker inner end of the spindle 49 a raceway for the bearing of the same description. 100 By rotating the plate 47 through a certain angle the pulley 50 can be forced against the belt on the pulley 38 to tighten the same to any required degree and all friction is eliminated.

105 From the above description, it will be seen that I have produced an exceedingly compact and well-poised arrangement of parts wherein the flywheel, driving pulley and tightener are all carried by the closure 110 plate 11, the flywheel on the inside of the crank case balancing the other parts on the outside, wherein all friction is avoided; and whereby all weight is lifted from the power shaft 6, leaving this element free from 115 every force except torsion and making possible a power shaft of comparatively small size to receive the thrust of the piston. It will also be noted that the flywheel, pulley, idler and mounting plate therefor, are all 120 disposed to one side of the piston rod. The combined mass of these parts is partly counteracted for igniting the fuel on the opposite side of the rod 4, in the chamber inclosed by the extension 14. As a result 125 the body of the cylinder and piston is disposed substantially over the center of gravity of the crank case and all the parts

associated therewith, whether on the inside or the outside of the same, producing ideal conditions of equilibrium for the whole engine. This part of my invention will now be set forth.

The magneto is supported at one end in the extension 14 by means of a journal box or bushing 56, mounted in an opening located in the center of the web 15. This opening is surrounded by a flange 58, in the magneto chamber, and this flange supports a bearing ring 59. A journal 60 on the field of the magneto fits into this ring, and the armature has a spindle 61 which projects through the bushing 56 into the flywheel chamber. This spindle is to be in exact alinement with the power shaft 6, as nearly as is practicable and is driven from the crank pin 7. The opposite end of the magneto is supported by a plate or spider 62 secured in the outer end of the extension 14 by being bolted to internal lugs 63. This spider has a central bearing opening into which is fitted the circuit breaker casing on the magneto frame at the adjacent end of the armature; and the cover 17 is preferably secured on the end of the extension by screws 64 passing through lugs 65 on the inside of the cover and engaging threaded apertures in the plate 62. Of course, the rim of the cover 17 can be threaded and made to engage corresponding threads on the end of the extension, if one wishes.

In order to insure the proper operating of the magneto whether the spindle 61 and shaft 6 be in perfect alinement or not, I connect the magneto to the crank pin by a compensating device which allows for any lateral play of the shaft and spindle. In applying the compensating device, I form a slot 66 in the end of the spindle 61 in the flywheel chamber and this slot 66 receives a bent arm 67 made preferably of spring steel and projecting from the edge of a disk 68. This arm and disk are shown as made in one piece, but I may make them in separate pieces if the latter construction should prove preferable. I mount the disk 68 on the pin 7 between the rings 18 and 19 and the nut 31 and I prefer to recess the face of the disk adjacent the bearing rings and place therein a wear ring 69. Hence if the spindle 61 and spindle 6 should ever get out of alinement, the end of the arm 67 will slide in the slot 66, radially of the spindle 61 and the rotation of the armature at the same speed as that of the shaft 6 will continue. This construction also avoids the necessity of machining, boring and finishing the parts with absolute accuracy. If the spindle 61 and 7 were connected by a rigid arm an inaccuracy of a few thousandths of an inch in the alinement of spindle 61 and 6 would produce objectionable strains. By the improved construction shown such

strains are eliminated and such an inaccuracy is immaterial.

The plate 11 is held on the crank case by bolts 70, and perforated lugs 71 are provided on the case to secure the motor to the carrying frame. An oil cup may be formed on the plate 11 to lubricate the shaft 6, and a suitable tap, closed by a plug 73 may be located in the bottom of the crank case.

When my engine is mounted on the framework which is made to carry it the crank case forms a central support for the cylinder and the magneto on one side of the axis thereof balances the flywheel and pulley on the other, thus producing equilibrium as nearly as is possible under practical conditions. The magneto is always positively and accurately driven directly from the flywheel and access can be had thereto at any time by taking off the cover 17. Furthermore, I mount the magneto in the extension 14 so that the magneto can be shifted around the armature, and the advance or retardation of the spark controlled accordingly. A suitable connection to the magnets passes through the extension 14 to a suitable operating mechanism to serve this purpose. Moreover, by forming two chambers in the crank case, I can obtain access to either the magneto or the flywheel, and piston connections without interference with the other, and at the same time leave enough free space in the fly-wheel chamber to provide for compressing air to force the fuel into the power chamber.

The balancing of the flywheel with respect to the pulley and tightener is another point of great practical advantage in that it prevents the plate 11 from buckling or warping; and the fact that no weight rests upon the shaft 6 greatly lessens the danger of this shaft ever twisting off or otherwise getting broken, a thing which might possibly happen if the shaft were subjected to not only a torsional stress but a bending moment also.

To obtain access to the flywheel chamber the operator need only remove the nut 41. The pulley 38 can then be taken off likewise the plate 47, after removing the nut 37 and unscrewing the ball bearing for the pulley. The latter, by the way, may have recesses in its face filled with plugs to afford a greater degree of frictional engagement with the belt, as disclosed in my prior application, Serial No. 663,112, of November 29th, 1911. Then it is only necessary to unscrew the fastening bolts for the plate 11.

Another matter to which I desire to call attention is the fact that the antifriction bearing for the flywheel is secured to the plate 11 by the flange 29 and wear plate 34, and when the plate is removed, slipping the tight bushing out along the shaft 6, the antifriction bearing will be drawn out of the recess 24 in the wheel 5, with it.

I desire to have it understood that the drawings and description disclose but one embodiment of my invention and that I do not care to be limited as to the scope and extent of my invention to the exact construction set forth. On the contrary, I reserve to myself the right to make such changes in the shape, size and arrangement of the parts as may be necessary in order to give to my engine the form that will prove most successful in practice.

Having thus described my invention, what I claim as new and desire to protect by Letters-Patent is:—

- 5 1. A crank case comprising a pair of chambers in axial alinement, an extension projecting from the walls of both chambers at right angles to said axis and communicating at its inner end with one of the same and a cylinder secured to said extension.
- 10 2. A crank case including a magneto chamber having a partition separating the same from the body of the case at one end and a removable cover for the other end, a bearing for the magneto armature carried by the partition, and a plate adjacent the cover having a bearing therein to support the other end of the magneto.
- 15 3. In combination, a crank case including a removable closure plate, a flywheel on one side of said plate, a driving pulley on the other side of said plate, and a shaft carrying said flywheel and said pulley passing through said plate and supported solely by the latter.
- 20 4. The combination of a crank case having an apertured end, a bushing carried by said end and projecting through the same, a shaft from the inside of the case to the outside of the same received in said bushing, a fly-wheel at the inner end of the shaft, a pulley at the outer end of the same, and bearings between the exterior of said bushing at opposite ends and said wheel and said pulley.
- 25 5. The combination of a plate having an aperture therein, a bushing in said aperture projecting from both faces of the plate, a shaft passing through the bushing, wheels on its ends adjacent the plate, and separate roller bearings between said wheels and the exterior of said bushing to cause the bushing to carry the weight of the wheels independently of the shaft.
- 30 6. The combination of a crank case end wall, a bushing projecting therethrough, a shaft passing through the bushing, a wheel on the shaft having a recess receiving one end of the bushing, and an anti-friction bearing between the exterior of said end of the bushing and the wall of the recess to cause the weight of the wheel to be borne by the bushing.
- 35 7. The combination of a bushing, means for supporting the same, said bushing hav-
- ing a projecting flanged end, and an anti-friction bearing carried on said end and retained between said flange and the supporting means.
- 40 8. The combination of a bushing, means for supporting the same, said bushing having a projecting flanged end, a plate between said end and the supporting means, and an antifriction bearing on the bushing between the flange and the plate.
- 45 9. In an engine the combination of a crank case, a flywheel inside the same adjacent one end, externally located transmission devices, a shaft secured to the flywheel and passing through the said end, said wheel having a crank pin connected to the engine piston, a magneto adjacent the opposite end of the crank case and separated from the flywheel by a partition, and means for connecting the magneto to be driven when the piston is in motion.
- 50 10. A crank case formed of an integral metal body portion having a partition subdividing it into a fly-wheel chamber and a magneto chamber, a removable end wall for the fly-wheel chamber, a shaft, a fly-wheel supported solely by said end wall, an end wall for the magneto chamber, and a magneto supported within said chamber independently of either end wall.
- 55 11. A crank case formed of an integral metal body portion having a partition subdividing it into a fly-wheel chamber and a magneto chamber, a removable end wall for the fly-wheel chamber, a shaft, a fly-wheel supported solely by said end wall, an end wall for the magneto chamber, a magneto supported within said chamber independently of the last mentioned end wall and having its shaft projecting through said partition approximately in line with said first mentioned shaft, and driving connections between said fly-wheel and said magneto shaft and operating irrespective of lack of exact alinement of the two shafts.
- 60 12. A crank case having a body portion, including a partition substantially in a plane parallel to the plane of movement of the crank, a removable end wall, a shaft projecting through said end wall, a fly-wheel carried by said shaft adjacent to but spaced from said partition, said shaft and said fly-wheel being supported solely by said end wall, a magneto upon the opposite side of said partition and having its shaft projecting through the latter, and driving connections between said fly-wheel and said magneto shaft.
- 65 13. A crank case including a body portion subdivided into two compartments in axial alinement, a fly wheel within one of said compartments, a support for said fly-wheel projecting through an outside end wall of said last mentioned compartment, and a magneto within the other compartment and

having its shaft projecting through the wall between said compartments.

14. A crank case including a body portion, oppositely disposed, removable end walls, a partition between said walls subdividing said crank case into two compartments, a drive shaft projecting through one of said end walls into one of said compartments, and a magneto supported in the other compartment independently of the other

end wall and having its shaft projecting through said partition.

Signed at New York city in the county of New York and State of New York this 4th day of December A. D. 1913.
